CLAIM

The ornamental design for a machine tie down device as shown and described.

DESCRIPTION

FIG. 1 is an isometric assembled view of a machine tie down device;

FIG. 2 is an isometric exploded view of the machine tie down device;

FIG. 3 is an isometric view of a top plate of the machine tie down device;

FIG. 4 is a top view of the top plate of the machine tie down device;

FIG. 5 is a bottom view of the top plate of the machine tie down device;

FIG. 6 is a front view of the top plate of the machine tie down device;

FIG. 7 is a side view of the top plate of the machine tie down device;

FIG. 8 is an isometric view of a bottom plate of the machine tie down device;

FIG. 9 is a top view of the bottom plate of the machine tie down device;

FIG. 10 is a front view of the bottom plate of the machine tie down device; and,

FIG. 11 is a side view of the bottom plate of the machine tie down device.
